POCKET GUARD

Warner R. Buxton, Longmeadow, Mass.

Application September 21, 1935, Serial No. 41,594

4 Claims. (Cl. 2—250)

This invention relates to an improved pocket guard for use in preventing a billfold, purse, pocket-book or the like from falling out of the pocket or from being surreptitiously abstracted 5 from the pocket.

The invention has for an object the provision of a pocket guard, consisting of a strip of springy material, adapted to be connected preferably in a manner to permit swinging movement, to one 10 wall of a pocket near the upper edge thereof and to be inserted into the pocket a substantial distance to overlie the pocket-book, or other article in said pocket, and to also extend alongside said article and tend to press the same toward and 15 against said wall.

The invention is characterized in that the 20 guard is of such length relative to the pocket that it cannot be swung out of the pocket solely by movement about its point of pivotal attachment to the pocket wall and it cannot be withdrawn 25 from the pocket at all without bending it to a very large degree (into substantially loop form) and, in so doing, the resilient guard is placed under such stress that it exerts substantial pressure 30 against one of the pocket walls and through such wall to the body of the person for the purpose of effectively warning him of the attempted theft.

The invention is also characterized in that the 35 guard and billfold cannot simultaneously be withdrawn from the pocket and in that, on any attempt to do so, the guard will function in cooperation with the pocket wall to bind the billfold more tightly in place. This action results be- 40 cause the guard is stiff enough so that it does not bend materially or buckle when the billfold is pulled up against it, and because of the position of the guard alongside the billfold in substantially straight form, whereby the guard will be cammed inwardly as the billfold is pulled upwardly and the upper edge of the pocket wall will be pulled 45 inwardly over and down upon the top of the billfold to effectively hold it against removal from the pocket.

These and other objects will more particularly appear as the detailed description proceeds and will be pointed out in the appended claims.

The invention will be disclosed with reference to the accompanying drawing, in which:

50 Fig. 1 is a face view of a pocket guard embodying the invention;

Fig. 2 is a sectional view taken on the line 2—2 of Fig. 1;

Fig. 3 is a side elevational form of a clasp for 55 fastening the guard to the pocket;

Fig. 4 is a fragmentary exterior view of a garment showing the guard in place in one of the pockets thereof;

Fig. 5 is a sectional elevational view taken through such pocket and showing the guard; and 5

Fig. 6 is a view, taken similarly to Fig. 5 but showing the position which the guard assumes when one attempts to remove the billfold without first removing the guard.

Referring first to Figs. 1 to 3 of this drawing; 10 the pocket guard preferably consists of a member in the form of a substantially straight and flat strip which is flexible and resilient. In the particular form shown, this member is a composite one, made up of a strip 10 of tempered steel, 15 which is very thin (having a thickness of a few thousandths of an inch, for example) and a doubled over strip 11 of leather or the like. The leather 11 is drawn through a loop 12 and doubled over to form a member of two plies between which the strip 10 is placed. These two plies of leather 20 are then sewed or otherwise secured, along the line 13, just below the lower bar of loop 12, and along the lines 14 near the side edges and the free end edge. It is preferable that the reinforcing spring strip 10 extend from end to end of the leather strip, substantially as shown. 25

As far as the functioning of the device is concerned, the leather 11 might be omitted and sole reliance placed upon the strip 10. However, it is 30 desirable to have the metal strip covered by a sheath of softer material in order to avoid wear on the pocket. Also, the appearance of the article is improved by the use of the leather sheath; 35 and the leather offers a simple and inexpensive means for attaching the spring metal strip to the lower cross bar of loop 12. Moreover, this construction enables the width of the guard to be increased to extend over as much of the pocket width as is desired solely by an increase in width of the leather and without a corresponding increase in the width of the spring strip 10. The 40 dimensions of this strip 10 cannot be materially changed without effecting the degree of its resiliency but the leather covering can be increased in width to any desired degree without substantially increasing the stiffness of the guard. 45

The guard, thus far described, is adapted to be secured at one end by any suitable means to one wall, usually the outer wall, of the pocket 50 of a garment. As an illustrative example of one such means which I consider suitable for the purpose, I have shown in the drawing a common form of clasp. This clasp comprises a U-shaped piece of metal 15, within which is mount- 55

ed a similarly shaped piece 16 of spring metal, the arms of which are provided near their outer ends with opposed spurs 17. A lever 18, mounted in trunnions 19 on one arm of member 15 has 5 a part 20 effective, when lever 18 is swung from the position shown in Fig. 3 upwardly into parallelism with member 15, to engage one arm of the spring strip 16 and move it toward the other to clamp a portion of the cloth wall of the pocket 10 therebetween. This clasp is secured, as by soldering or any other suitable way, to the upper cross bar of loop 12. The arrangement is preferably such that the guard may swing relatively to the clasp,—the guard in this case turning on 15 the lower cross bar of loop 12. Various other means might obviously be used for the purpose, which is simply to secure one end of the guard, preferably in a manner to enable pivotal movement, to a wall of the pocket, and the one means described is to be taken merely as illustrating one of many that are suitable.

In use, the guard is attached to one wall of a pocket near the upper edge thereof. Conveniently, the outer wall of the pocket is used especially where the fastening device is of the clasp form shown. However, the guard might be attached by other means to the inner wall of the pocket. The usual and best method of attachment is shown in Fig. 5 in connection with 30 a pocket *p* formed in a garment *g*. The outer and inner walls of the pocket are shown at *w* and *w'*, respectively. The outer wall *w* lies just inside a part *g'* of the garment, so that in effect the outer wall is of double thickness. Also, the 35 upper edge of the part *g'* is folded down over the wall *w* so that the upper edge of the outer wall is of three ply thickness. To such edge the clasp is applied and fastened as shown, the lever 18 being located by preference inside the pocket 40 where it is normally inaccessible,—being covered by the guard. The guard can occupy two positions, one inside and one outside the pocket *p*. With the guard hanging pendant from the loop 12 of the clasp and outside the pocket as 45 indicated in dotted lines in Fig. 5, one places the billfold *b*, or other article in pocket *p*. Then the guard is swung upwardly until it occupies a position in which it extends approximately horizontally outward from the bar 12 of the clasp and, 50 while thus positioned, its free end is bent upwardly and then downwardly until its lower and free end lies in the mouth of the pocket and against the rear wall *w'* thereof, or nearly into substantially the form of a loop as shown by 55 the upper set of dotted lines in Fig. 5. Ordinarily, if the guard is released when thus positioned, it will, because of its tendency to resume a straight form, enter the pocket *p* and assume a position more or less like that shown by full lines in Fig. 5. If it does not thus automatically enter the pocket, it may readily be thrust downwardly. When properly inserted, the guard lies between the billfold *b* and the rear wall *w'* and is very nearly, although usually not quite straight. 60 Usually, the spring strip of the guard is under some tension and its free end presses against wall *w'* and its pivoted end presses against the upper edge of wall *w* while an intermediate part presses the billfold toward wall *w*. 65 It is to be noted that the guard is of such length that it cannot be swung, about its pivotal connection with the clasp, out of pocket *p*. Its length is greater than the maximum width of pocket *p*, even when the pocket is distended as 70 much as possible. Particularly, the guard is of

such length that it cannot be pulled out of the pocket without bending it nearly into loop form and more or less reversing the method used in its insertion into the pocket. Because of this arrangement, the pickpocket will find it impossible 5 to lift the guard out of the pocket without attracting the attention of his intended victim. This follows because, when the guard is bent as is necessary, preliminary to its removal, it is also placed under increased tension and the inner and lower end of the guard will press heavily 10 against the rear wall of pocket *w'* and the latter against the person of the wearer in a manner certain to attract his attention.

If the pickpocket attempts to remove the billfold without first removing the guard, he will be frustrated. It will be seen from Fig. 5 that the guard and outer wall *w* are disposed in upwardly converging relation and together define 15 an inverted V and, when the billfold is lifted 20 to it rides into this V. As the billfold is pulled up, it forces the guard inwardly toward wall *w'* and, as the guard moves inwardly, it pulls inwardly the middle part of the upper edge of pocket *p* until finally a condition such as shown 25 in Fig. 6 exists. Here, the upper edge of wall *w* has been pulled down over the top of the billfold until the clasp engages it. Any further upward pull on the billfold will be exerted on the clasp and on the inturned upper edge of the 30 pocket and not against the guard itself. This guard, being resilient, and capable after deflection of resuming its normal straight form, does not bend materially when the billfold is pulled up against it but is cammed inwardly and causes 35 the inturning of the upper edge of the pocket to effectively block the removal of the billfold. The guard cannot buckle, as might a leather piece which is much more flexible and much less resilient. Naturally, it is so very much stiffer 40 than the pocket wall *w* that the latter bends first and is pulled inwardly, as described and the guard becomes practically straight, as shown. Thus, the billfold cannot be removed unless and until the guard has been withdrawn from the 45 pocket.

It will be clear also that the billfold cannot accidentally slide out of the pocket for like reasons. The farther it slides toward the mouth of the pocket, the more tightly it is held against 50 passage through said mouth.

To release the billfold, one reaches into the pocket behind the guard and grasps it at a point considerably away from the clasp and bends it, pulling upwardly at the same time. The spring 55 pressure will force the upper edge of wall *w* outwardly and cause the clasp to turn until it extends nearly horizontally outward, thus moving outward the pivot point of the guard and facilitating the further bending of the guard into 60 the nearly circular or loop form necessary for its removal. When the guard has been completely withdrawn from the pocket, it is swung outwardly about its pivotal connection with the clasp to lie wholly outside the pocket in a pendant position, leaving the mouth of the pocket 65 entirely unobstructed so that the billfold may be easily and freely withdrawn. Even the clasp is out of the way because the weight of the guard, acting on the clasp, bends the upper edge 70 of the pocket outwardly as indicated in Fig. 5.

The construction and arrangement is such that even the most dexterous pickpocket could not hope to remove at one operation both the guard and the billfold. As has been seen, it 75

cannot be done merely by lifting the billfold. And the necessity of springing the guard and bending it to the large degree described is all that the operator can do at one time. He has 5 no chance to lift up on the billfold at the same time. Two separate operations are therefore necessary in order to get the billfold out of the pocket.

The invention thus provides a pocket guard 10 which is effective to prevent accidental loss or theft of a billfold or the like from a pocket. The invention is characterized in that the guard is a springy member, which has to be bent to a substantial degree and thus placed under stress, 15 as a prerequisite to its withdrawal from the pocket. And the placing of the guard under stress results in application of pressure to the owner of the billfold, thereby warning him of the attempted theft. The arrangement is also 20 characterized in that the guard and billfold cannot be simultaneously withdrawn from the pocket in one operation. Successive operations are necessary for this purpose,—the guard must be withdrawn first and in the act of withdrawing 25 the guard an effective warning of the impending theft is given.

What I claim is:

1. A guard for preventing loss or theft of a billfold or the like from the pocket of a garment, 30 comprising, a strip of springy material having a normal shape such that it may extend lengthwise into the pocket and having sufficient resiliency to enable it to be bent into substantially loop form and resume its normal shape when released, 35 means for fastening said strip near one end to one wall of the pocket near the upper edge thereof, said strip adapted to be inserted in the pocket to overlie the top of and lie along one side of the billfold and having a length such as to prevent it from being inserted in or removed from the pocket without first bending it substantially 40 into the aforesaid form.

2. A guard for preventing loss or theft of a billfold or the like from the pocket of a garment, 45 comprising, a strip of springy material having a normal shape such that it may extend lengthwise into the pocket and having sufficient resiliency to enable it to be bent into substantially loop form and resume its normal shape when released, 50 means for pivotally suspending said strip from the

top edge of the pocket so that it may hang downwardly either inside or outside the pocket, said strip having a length such as to prevent it from being inserted in or removed from the pocket solely by pivotal movement relative to said means and such as to require springing of said strip substantially into the aforesaid form. 5

3. In combination with a member adapted to be inserted in and withdrawn from the pocket of a garment, of a device having a pivotal connection 10 with said member near one end of the latter and having fastening means for securing it to said pocket near the top edge thereof, so that said member may hang downwardly from said device either inside or outside said pocket, said fastening 15 means being applied to the inside of said pocket below said pivotal connection and being covered and concealed by said member when the latter hangs downwardly inside the pocket, whereby 20 removal of the fastening means without first withdrawing said member from said pocket is prevented.

4. In combination with a garment, having inner and outer pocket-forming walls connected together along the bottom and both sides and forming between them a pocket open at its upper end, said pocket adapted to contain a billfold, a strip of springy material having a substantially straight normal shape and having sufficient resiliency to enable it to be bent into substantially loop form 30 and resume its normal form when released, means pivotally connecting one end of said strip to said outer wall near the upper edge thereof at the open end of said pocket, said strip having a length such as to prevent it from being inserted in or 35 removed from said pocket without first bending it substantially into the aforesaid form, said strip adapted to be inserted in the pocket with its lower portion disposed between said inner wall and billfold, its upper portion then overlying the billfold and extending from said upper edge in 40 downwardly diverging relation with the outer wall, said upper portion being located in the path of upward movement of the billfold and adapted to be moved by the billfold on an attempted withdrawal of it from the pocket and forced toward the inner wall, drawing the upper edge of 45 said outer wall inwardly and downwardly over the upper end of the billfold.

WARNER R. BUXTON. 50
